UNITED STATES PATENT OFFICE

2,262,892

ELECTRICAL HEATER

William H. Heard, Portland, Oreg.

Application November 25, 1940, Serial No. 367,087

1 Claim. (Cl. 219—38)

My invention relates to improvements in electrical heaters, and the primary object of my invention is to provide an arrangement of this character wherein component parts of the heater are constructed to hold heat applied thereto by the electrical heating element, so that during the course of a heating operation the energization of the heating element may be reduced or cut off, with corresponding savings in the cost and time, without reduction of heating effect.

Another important object of my invention is to provide an electrical heating device particularly adaptable to replace gas, oil and coal heating elements in domestic and industrial furnaces and heating plants, with consequent savings in cost and operation and upkeep of such furnaces and heating plants.

Another important object of my invention is to provide an electrical heating arrangement of the character indicated which is automatically thermostatically controlled so that a predetermined or desired adjusted temperature may be uniformly maintained, and through whose use and operation flues, combustion chambers, fire pots, and their attendant ash and products of combustion are eliminated and rendered unnecessary, with consequent savings in expense of removal and disposal and reconditioning of the parts deteriorated and the presence thereof.

Other important objects and advantages of my invention will be apparent from a reading of the following description taken in connection with the appended drawings, wherein for purposes of illustration are shown preferred embodiments of my invention.

In the drawings:

Figure 1 is a general side elevational view of the heating device per se.

Figure 2 is a transverse vertical sectional view taken through Figure 1.

Figure 3 is a horizontal sectional view taken through Figure 2 along the line 3—3 and looking downwardly in the direction of the arrows.

Figure 4 is a perspective view of one of the component sections of either the inner or the outer form.

Figure 5 is a bottom plan view of the sectional base, showing one of the component sections separated from the others, and

Figure 6 is a general transverse vertical sectional view taken through a heating enclosure in which the heating device is the source of heat, and showing sections of the outer form of the heating device removed, and with thermostatic control arrangements incorporated.

Referring in detail to the drawings, the numeral 5 generally designates the device which is composed of a substantially circular base 6 consisting of ninety degree segments 7 on the opposite ends of which are tongues and grooves 8 and 9, respectively, which mate with the tongues and grooves of the adjacent segments to form a flat circular plate. The apex portions of the segments 7 are cut off to provide an opening 10 to pass the thermostatic bulb 11 shown in Figure 6. One of the segments 7 is provided with a hole 12 to pass the wires which lead from the opposite ends of the helical heating element or wire 13 which is spirally wound on the inner form to be described, the said wire passing through a suitable conduit 14 to a thermostatic control box 15 on the outside of a furnace casing 16, the enclosure to be electrically heated. The thermostatic bulb 11 has its tube 17, like the conduit 14, passing through the side wall of the enclosure 16 to enter the control box 15. This control box may be of any suitable conventional type enabling permanently fixing or temporarily adjusting the sensitivity of the thermostatic control for cutting in and cutting out the heating element 13 with respect to a suitable source of current properly connected to the control box as indicated by the numeral 18. The conduit 14 and the tube 17 pass downwardly through an opening 19 in a suitable support 20 on which the base rests in proper relation to the side walls and the top of the enclosure 16 as exemplified in Figure 6.

An important advantage of having the base 6 and the inner and outer forms of the heating device in sectional construction is that the sections can be passed through the enclosure opening 21 and easily assembled within the enclosure, whereas the assembled heating device might otherwise be too large to pass the opening 21. The base 6 may suitably rest on the support 20 in the enclosure to be heated, and be secured to the support in any suitable manner. The top of the base has inner and outer circumferential grooves 22 and 23 concentric with respect to the base for retention of the conforming annular ribs 24 and 25 on the lower edges of the inner and outer forms to be described, whereby the inner and outer forms are assembled on the base and the sections of the base assembled with respect to each other so that there is no heat lost through the joints thus effected.

The inner form which is shown and designated 26 consists of a hollow acorn shape formed of triangular segments 27 shown in Figure 4 of the drawings and having on one side edge a

tongue 28 and on the opposite side edge a groove 29 and on its lower edge a tongue 30 for engaging in the groove 22 in the top of the base 6, with the tongues and grooves of the various segments 27 interengaged so as to assemble the segments or sections relative to each other and to effect joints therebetween which prevent the passage of heat therethrough, the resulting form 26 being acorn shaped.

The outer form which is shown and designated 31 is shaped substantially exactly like the inner form 26, but is larger in diameter and taller so as to be circumferentially spaced at substantially equal distances from every part of the inner form 26. The outer form is formed by triangular sections similar to the sections 27 and similarly provided with tongues and grooves for assembly with the groove 23 in the base 6 and for interengagement with the tongues and grooves of the companion sections or segments, whereby all of the segments constituting the outer form are held in assembled relation.

The outside of the inner form 26 is wound with a helix 13 of suitable heating element wire with the upper end of the helix led off down through a sufficient opening in the upper end of the inner form as illustrated in Figure 6, and with the lower end of the helix led off into the interior of the inner form 26 as also illustrated in Figure 6, both of the resultant leads passing into the conduit 14 leading to the control box.

The base 6, the inner form 26, and the outer form 31, are preferably formed of fire-clay or other heat-holding, noncombustible material such as "Kast Set."

In the operation of the device of the invention, the current supply 18 is applied through the control box 15 to the heating element 13 so as to cause such heating element through the resistance to passage of electricity therethrough to attain high temperature and thereby heat the inner form 26, the space 32 between the inner and outer forms, and the outer form 31 and the base 6 so that the inner and outer forms and the base may become a cherry red or approach incandescence, or

otherwise exhibit a required temperature for the space to be heated. When the desired or set temperature is reached, the thermostatic control 15 is operated by its bulb 11 so as to cut off the energizing current until such time as the temperature of the heating device falls and re-energization of the heating element 13 is required to restore or maintain the desired or set temperature.

Although I have shown and described herein preferred embodiments of my invention, it is to be definitely understood that I do not wish to limit the application of my invention thereto, except as may be required by the scope of the subjoined claim.

Having described the invention what is claimed as new is:

A heating device comprising a circular base composed of a plurality of triangular-shaped segments having their apices cut off to provide openings, and having their opposite ends provided with tongues and grooves, respectively, for mating with the tongues and grooves of the adjacent segments, one of said segments having an orifice therein, an inner hollow form rising from said base, an outer hollow form rising from said base concentrically around and spacedly enclosing said inner form, said inner and outer forms being of heat-holding, non-combustible material and being formed of segments in edge-to-edge relation, the lower edges of the segments comprising at least one of said forms and the top of the base being formed with companion tongues and grooves to provide separable rigid connection of the assembled segments of the forms and the base, a helical heating element spirally wound on the inner form and having the wires leading from its opposite ends passed through the orifice in the one segment of the base, a thermostatic bulb mounted in the opening provided in the apex portion of the segments, and an electric control box connected to the wires leading from the helical heating element and connected to the thermostatic bulb.

WILLIAM H. HEARD.
